L. Kidder,
Constructing Cisterns,
Patented Jan. 21, 1835.

See "Riddle"
Letters Patent

The subscriber referred to in these Letters Patent and making boast of the same containing a description and the novelty of the said Secret Riddle himself of his improvement in the construction of Cisterns or vessels formed in the earth for containing water and other fluids.

The Specification of Secret Riddle's improvement in the construction of vessels formed in the earth for containing water and other fluids in the words of the said Riddle. This affidavit describes in the first place his improved mode of constructing such vessels & that other skilled in this art may construct the same.

Having excavated in the earth a space somewhat larger by two feet in every way than the horizontal dimensions of the vessel to be constructed and made the bottom or ^{floor} thereof horizontal and smooth. The operator must place or put together or construct the mould on said bottom as herein after described. The mould be ing constructed in the form externally which the cistern is to have internally. The operator by sift ing, paddling and spreading the earth particles, it between the mould and the natural earth, as compactly & firmly as it may be done, adding as the different kinds of earth used may require more or less clay or lime at dissolution, and this packing of the earth around the exterior of the mould is continued till the whole of the desired shape is obtained, and then it is suffered to stand sufficient time to become hard and firm enough to preserve its form after the mould shall be removed. The mould may be constructed in the instance of a cistern, in a jar like form as follows. Let the mould be formed in pieces such as would be made of a jar taking for example a lid one six inches in diameter, parallel to its bottom, and then these sections cut at right angles. It is manifest that a mould formed of pieces thus when laid up together on the floor of the cistern in the shape designed can easily be joined together while the earth is packing about it, and be easily

19

O. C. 1835. 1835

arranged within the earth, as becomes sufficiently solid, by taking the pieces, and
spoil and working them up through the walls of this pan from outside.
This placing them the operator will then plaster the hydraulic, or water
cement upon the surface of the earth to be shaped in the bottom and on
the floor or bottom thereof, putting on as many coats, of cement, as
may be deemed sufficient at discretion. Moulds of various shapes, may
be formed with or without supports, but in all cases where the top or
top of the earth or vessel is to be formed of earth and cement
as above, the mould must be shaped more or less in the shape
of a sphere or ellipsoid, so as to bear its own weight, and that of
the superincumbent earth. But where the shape does not require
this, the mould may be made in pieces in any convenient manner
for the case in such case where cover is wanted will be made of wood
or other material at convenience.

This applicant next describes the principle of his invention as
follows. The principle of this invention consists, in the mode
of forming the vessel intended, with earth substantially as aforesaid
by means of a removable mould, and by plastering Hydraulic or
water cement upon the earth thus shaped, covering the sides or
walls and also the bottom and top or cap of said vessel, if the
top be formed as aforesaid little one or more coats, of said cement
so as to make said vessel sufficiently light to hold water or other
fluids or liquors which can be held by cement.

This applicant does, not claim as his invention the mere plac-
ing of cement upon the earth or earthy walls. This, he con-
siders, is a use of cement which belongs to the public, of common
right, neither does he claim the mere application of hydraulic or
water cement or any other cement to the constructing in any man-
ner of all or any part of vessels of any kind designed to contain fla-
ids of any sort. nor does he claim the mere use of gravel to stiff-
en or harden the mortar but considers this application of such
cement and the use of gravel or earth in the construction of such
vessels, as a matter of common right, as much as water. But the

claim of this supplement in respect to the construction of such a pot, consists as aforesaid in the mode or method above described of forming vessels intended to be constructed to hold water or other fluids aforesaid. And this applies and further describes the various modes or purposes for which he contemplates the application of his said invention viz. In the construction of vessels from necessary bathtubs, and otherwise, for containing water or other fluids, and liquors, and those vessels to be constructed with walls or sides in any form, and with or without tops, or covers.

And in respect to the moulds to be used there may be constructed in parts so as to be conveniently removable, and sound for future use, or moulds may be constructed specially from a particular structure, and be broken to pieces to be removed, or as to be useful for future use. But the former is the better and preferable mode of constructing the moulds. It also when the top of a pot is formed of earth, the part or parts of the mould which sustain the top may be sustained by a right post, resting on the bottom, after this be plastered and the walls also nearly up to the top to be covered with cement, and thereby the vessel or cover may be fit for use without waiting for the consolidation and hardening of the earthy top, which will be the necessity to ensure if supported by the mould a long time, or till it be nearly dry. Then these parts of the mould supporting the top being removed, the top should be plastered with cement forthcoming. The better and preferable mode however is to plaster the whole interior at the same time as aforesaid, thus making a better particle of the cement, as is obvious to workmen in the trade. Witness my hand this 6th January 1835
